UNITED STATES PATENT OFFICE.

WALTER JACOB SANTMYER, OF SEATTLE, WASHINGTON.

WASTE-FUEL BURNER.

1,304,380.

Specification of Letters Patent. Patented May 20, 1919.

Application filed June 13, 1917. Serial No. 174,581.

To all whom it may concern:

Be it known that I, WALTER J. SANTMYER, a citizen of the United States, residing at Seattle, in the county of King and State of Washington, have invented certain new and useful Improvements in Waste-Fuel Burners; and I do declare the following to be a full, clear, and exact description of the invention, such as will enable others skilled in the art to which it appertains to make and use the same.

My invention relates to that class of devices designed for consuming waste fuel such as coal dust and the well known poor grades of coal such as slack. I am aware that numerous devices have heretofore been designed for carrying out the same purpose as my invention, but they have been more or less inefficient due to numerous causes.

The object of my invention, therefore, is to provide a simply constructed and inexpensive burner, yet one which will be highly efficient and durable.

With the foregoing general object in view, the invention resides in the novel features of construction and the unique combination of parts to be hereinafter fully described and claimed, the descriptive matter being supplemented by the accompanying drawings which form a part of this specification and in which:

Figure 1 is a top plan view of a furnace showing the application of two of the improved burners thereto;

Fig. 2 is a front elevation of Fig. 1;

Fig. 3 is a vertical longitudinal section on the plane of the line 3—3 of Fig. 2;

Fig. 4 is an enlarged horizontal section of one of the improved burners;

Fig. 5 is a transverse section of Fig. 4 on the plane of the line 5—5 thereof;

Fig. 6 is a longitudinal section showing a different form of nozzle; and

Fig. 7 is a transverse section of Fig. 6 on the plane of the line 7—7.

In the drawings above briefly described, a portion of a furnace is shown, this furnace embodying a fire box 1, the front wall 2 of said fire box being formed with one or more openings 3, two of such openings being shown. The openings 3 receive therein the reduced inner end 4 of a pair of outer drums 5, the body portion of said drums being located on the exterior of the furnace and being contracted at 6.

The drums 5 form passages as will be hereinafter set forth, to admit an abundant quantity of air to be drawn into the fire box by the fluid pressure blast yet to be explained, and said drums receive therein a pair of inner drums 7 which are positioned coaxially in said outer drums. The inner ends of the drums 7 are contracted at 8, said contracted ends being positioned adjacent the contracted portions 6 of the drums 5 as shown clearly in Figs. 1 and 3. Nozzles 9 extend coaxially into the drums 7 and preferably have their inner ends positioned adjacent the contracted ends 5 of said drums, the outer ends of said nozzles 9 being equipped with elbows 10 into which the powdered fuel to be consumed, is fed. Two blasts of air are also fed into the elbows 10, so as to insure a thorough mixing of the slack or the like with such air and at the same time to force the fuel into the fire box.

The force of the air and fuel discharged from the inner ends of the nozzles 9, creates a suction through the inner and outer drums 7 and 5 respectively, such suction drawing an additional quantity of air into the furnace to facilitate combustion, the outer ends of both drums being open so as to permit the air to readily enter. If required, however, said ends may well be equipped with suitable dampers (not shown).

Fuel supply pipes 11 lead to one end of the elbows 10 from suitable bunkers, whereas the nozzles 9 extend from the opposite ends of said elbows. These nozzles may be of the flat construction shown in Figs. 4 and 5, or may be of circular shape in cross section as depicted clearly in the form of the invention illustrated in Figs. 6 and 7. The fuel deposited into the elbows 10, is picked up by a fluid pressure blast discharged from branches 12 which extend from a pressure supply pipe 13, said pipe leading from a suitable blower 14, so that the mixture is discharged from the inner end of the nozzle 9 at which point it is ignited and is consumed to perform the required work. An auxiliary quantity of air is sprayed into the elbows 10, by means of suitable air spraying devices 15 which extend into said elbows from a pipe line 16 on the exterior of the furnace, said devices 16 being in longitudinal alinement with the center of the nozzles 9. This auxiliary quantity of air, being sprayed into the de-

vice, causes a much more thorough mixing of air with the powdered fuel and thus insures more perfect combustion at the delivery end of the nozzles.

- 5 In initially igniting the fuel, a pilot burner such as 17 is employed, said burner being illustrated for burning oil, although it could well consume any preferred fuel. When two of the improved burners are employed, as illustrated in the present embodiment of the invention, the burner 17 will be positioned midway between said burners and will extend through the front wall of the fire box, as shown clearly in Fig. 1, a suitable inlet 18 being provided for supplying an excess quantity of air to the burner. Similar passages 19 are shown in dotted lines in Figs. 1 and 2, for feeding an abundant quantity of atmospheric air to the flaming fuel at the delivery ends of the nozzles 9. This is shown for illustrative purposes, however, and other suitable air supplying means could well be employed. The burner 17 is supplied with oil through a suitable pipe 20 and by means of a branch pipe 21, steam may be fed to said burner to mix with the oil to increase combustion, said branch pipe extending from an arched steam pipe 23, said pipe having additional branches terminating in steam spraying devices 24, the latter being positioned in the space between the inner and outer drums 7 and 5 respectively. It is the office of the spraying devices 24, to supply a quantity of steam to the flaming fuel at the delivery end of the nozzles.

The bottom 25 inclines downwardly to the hopper shaped upper end 26 of an ash pit 27, said ash pit having a suitable water pipe 28 which supplies a sufficient quantity of liquid to prevent adhesion from taking place. There is thus no difficulty encountered in removing the ashes, as is the case when no water is supplied.

In operation, the fuel to be consumed is fed through the pipes 11 to the nozzles 9, by the blasts of compressed air or the like supplied by the branch pipes 12 and by the air spraying devices 15. A thorough mixing of the fuel and air takes place in the elbows 10, this mixture being then discharged from the inner ends of the nozzles, at which point it is ignited by the burner 17 or by any other suitable means which may be provided. During the operation of the device, a strong draft of air is induced through the spaces between the inner and outer drums and between the inner drums and the nozzles 9, this surplus air serving to increase combustion as does also the air supplied through the passages 18 and 19. Even the poorest grade of slack and other kinds of coal are burned thoroughly by the present invention and all ashes are deposited in the ash pit 27 so that the boiler tubes and flues are not clogged.

63 Furthermore, since these ashes do not reach

the smoke stack, there is no danger whatever of the latter depositing them upon the surrounding territory.

From the foregoing, taken in connection with the accompanying drawings, it will be obvious that although the improved burners are of comparatively simple and inexpensive construction, they are highly efficient and durable for the purposes specified as well as any others to which they are applicable. 75 Since probably the best results are obtained from the specific construction shown and described, this construction constitutes the preferred form of my invention. I wish it understood, however, that within the scope 80 of the invention as claimed, numerous minor changes may be made without sacrificing the principal advantages. Furthermore, although I have shown a plurality of the burners applied, it is obvious that on smaller 85 boilers and the like, only one may be necessary.

I claim:—

1. In a powdered fuel burner, the combination of a fire-box having a circular opening in its wall, an outer cylindrical drum on the exterior of said firebox having a contracted inner end disposed at said opening, a cylindrical inner drum in and spaced from said outer drum and having a contracted 90 frusto cone-shaped inner end disposed adjacent the contracted portion of said outer drum, the two drums being open at their inner ends and open to the atmosphere at the outer ends, a powdered fuel burning nozzle 100 extending into and spaced from said inner drum, an elbow from which said nozzle extends, a powdered fuel supply pipe leading to said elbow, an air pressure inlet into said elbow directed obliquely across the corner 105 or angle thereof, and an air pressure spraying device having a discharge head disposed in said elbow between said air pressure inlet and the outlet end of said elbow, and in line with the axis of such outlet end. 110

2. In a powdered fuel burner, an elbow, a powdered fuel supply pipe discharging into one end of said elbow, a fuel discharge nozzle communicating with the other end of said elbow, an air pressure inlet into said elbow 115 directed obliquely across the corner or angle thereof, and an air pressure spraying device having a discharge head disposed in said elbow between said air pressure inlet and the outlet end of the elbow, and in line with the axis of said outlet end. 120

3. A powdered fuel burner comprising an elbow, a pipe discharging into one end of said elbow for supplying powdered fuel thereto, a nozzle communicating with the 125 other end of said elbow, and a fluid pressure inlet directed across the corner or angle of said elbow for carrying the fuel through the nozzle in suspension and to prevent lodging of said fuel in said elbow. 130

4. In a powdered fuel burner, the combination of a fire-box having a circular opening in its wall, an outer cylindrical drum on the exterior of said fire-box and having a contracted inner end disposed at said opening, a cylindrical inner drum in and spaced from said outer drum and having a contracted frusto cone-shaped inner end disposed adjacent the contracted portion of 10 said outer drum, the two drums being open at their inner ends and open to the atmosphere at their outer ends, a powdered fuel burning nozzle extending into and spaced from said inner drum, means for supplying powdered fuel and fluid under pressure to 15 said nozzle, and a fluid spray pipe between the upper sides of said inner and outer drums and discharging against the contracted part of the latter, whereby the fluid will be directed downwardly into the mix- 20 ture of air and powdered fuel.
- In testimony whereof I have hereunto set my hand in the presence of two subscribing witnesses.

WALTER JACOB SANTMYER.
